UNITED STATES PATENT OFFICE.

EDWARD E. CLEMENT, OF WASHINGTON, DISTRICT OF COLUMBIA, ASSIGNEE, BY
MESNE ASSIGNMENTS, TO FREDERICK C. STEVENS, OF ATTICA, NEW YORK.

TELEPHONE-EXCHANGE SYSTEM.

1,107,147.

Specification of Letters Patent. Patented Aug. 11, 1914.

Application filed July 14, 1906. Serial No. 326,252.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems and has for its object the improvement of such systems in the manner which will be hereinafter pointed out.

The characteristic features of my invention are: (1) manually controlled connecting means for answering the calls of subscribers in an exchange; (2) automatic switching apparatus consisting of all relays arranged in decimal relation and adapted to connect the 20 manually connecting circuits with the wanted line; (3) step by step controlling means for the automatic switching apparatus; and (4) manually controlled keys or switches for working the controlling apparatus.

25 Briefly outlined, the present system comprises standard common battery line circuits terminating in jacks at the central office, each jack having its associated lamp and being adapted to receive the ordinary answering plug inserted by operators in the usual manner. Each answering plug is connected by a trunk line to a decimal set of relays, which for the sake of simplicity I shall illustrate and describe as containing 30 line terminals but which may also and obviously contain the terminals of other trunks for working in large systems. These relays are controlled by step by step means which themselves are actuated by an operator

40 through keys preferably associated with the trunks. The step by step means may be either step by step switches of the ordinary and well known type, having a circular series of contacts swept over by the arm or 45 arms moved around step by step by a magnet, or they may be step by step interlocking relays, these relays being in a double set of ten for the decimal relation, those of each set preparing those of the other alternately 50 for operation as the successive impulses come over their controlling circuits.

In making a connection in this system, the operator plugs in in response to the subscriber's call, takes the number in the usual 55 way by means of the listening key, and then

proceeds to manipulate her keys or impulse sender so as to set up the step by step device to the number wanted. This then closes the circuits of the appropriate tens and units relays of the decimal set, and by 60 the energization thereof the plug circuit is immediately connected to the desired circuit selected. In the case of systems from 100 to 10,000 lines or more, the operation is necessarily repeated as many times as there are 65 digits in the number wanted, each repetition effecting one stepping operation and the set of one group of decimal relays, whereby the calling line is switched to the thousands trunk wanted, and then through that and by 70 means of its decimal relays to the hundreds group and then through that and by means of the next set of decimal relays to the line wanted.

While I have described the step by step 75 relays herein, any skilled engineer should be able to substitute step by step switches, such switches being known and their operation well understood.

My invention is illustrated in the accompanying drawings wherein—

Figure 1 shows a subscriber's station, the line wires of which terminate in central office apparatus. Fig. 2 shows the operator's connective apparatus with a set of step by 85 step selective relays. Fig. 3 shows a set of connector relays which are controlled by the step by step relays in Fig. 2.

Referring now to Fig. 1, the subscriber's apparatus consists of the usual transmitter, 90 receiver, ringers, condenser, and switchhook. The line wires 1 and 2 from this station terminate in a line relay M through the normally closed contacts of the cut-off relay M'. When this relay M is energized the circuit of the line lamp L is closed. When the circuit of the cut-off relay M' is closed, the line relay is disconnected and the line wires are connected to the springs j and j' of the jack J.

Referring now to Fig. 2, the answering end of the operator's cord circuit terminates in the tip p and sleeve p' of the plug P. The answering end and calling end are separated by the condensers C and C'. The two 105 relays D and D' are bridged across the answering end and furnish battery to the calling subscriber as well as controlling the supervisory lamp L'. The two relays, E² and E³ are bridged across the calling end of 110

the trunk and supply talking current to the called subscriber, as well as controlling the supervisory lamp L^2 . The operator is provided with a sending device which I have 5 represented diagrammatically by the two push buttons X and X' . The spring x^2 of the button X is connected to the relay E , while the spring x is connected directly to battery. When this button is depressed, the 10 relay E is operated as one terminal is connected to ground. The operation of this relay closes the circuit of the relay F' which supplies battery to the contact e' of the relay E . The making and breaking of the contacts e , e' and e^2 operate the relays of the 15 set W in step by step order. The operator depressing the button X the first time energizes the relay E but while the button is held down, none of the relays in the set W 20 are affected, but when the button is released, the circuit of the relay H' is closed through the contact e' and e^2 as battery has been placed on the contact e' by the energizing of the locking relay F' . The operating of 25 the relay H' closes the circuit of the relay W' through the contacts h and h' . Now, when the operator depresses the button X the second time and the relay E is in an energized condition, the circuit of the relay 30 W' is closed through the contacts e and e' . When the pressure is again removed from the button, the circuit of the relay H^2 is closed through the contacts w' and w^2 of the relay W' . This operation can be kept up indefinitely, for every time the button X is operated, two relays of the set W are worked. The relays H in the lower row are simply the guard relays and are operated when the relay E is deenergized and place the relays 35 W' and W^2 , etc., in position to be operated 40 when the relay E is energized.

Taking Figs. 2 and 3 together, the relay W' when energized closes the circuit of the first tens relay T' . The relay W^2 when energized closes the circuit of the relay T^2 , while the relays W^3 , W^4 and W^5 control the relays T^3 , T^4 and T^5 . The relays T' and T^2 , etc., in the upper row are tens relays and each contains the multiples of ten lines and 50 for a 100 line system there would be ten of these relays. The drawing only shows five of these relays and each relay containing the multiples of only five lines. I have shown the relays in this manner for simplicity as 55 additional wiring would be confusing. The lower set of relays T^{11} and T^{12} , etc., are the units relays and each contains multiples of the contacts of the upper set or tens relays. The relay T^{11} being the first units relay, 60 contains the multiples of the first pair of contacts in each of the relays T' , T^2 , etc., while the relay T^{12} contains the multiples of the second pair of contacts of these relays. The trunk wires 7 and 8 are multipled to contacts in the lower set or units 65

relays. If the first tens relay T' and the first units relay T^{11} are energized, the trunk wires 7 and 8 will be connected to line 11 through the contacts t^{11} and t' , and if the third relay T^3 and the second units relay 70 T^{12} were energized, the trunk wires would be connected to line No. 32 through the contacts t^{12} and t^3 . The tens relays are the first set of relays to be operated by the relay set W and are provided with two windings, an actuating winding which is controlled by the relay set W , and a locking winding which is controlled by the relay F . The locking winding from each relay is connected to the common wire 16 leading to the 75 contact f^6 in the relay F , while the actuating windings are connected to the common wire 15 leading to ground through the contacts f^4 and f^5 of the relay F . Individual actuating wires 23, 24, 25, 26 and 27 lead to the normally open contacts of the relays W' , W^2 , etc. The units relays have only a single winding and are the second set of relays to be operated by the relay set W . The winding from the first units relay T^{11} 80 is connected in multiple with the actuating winding of the relay T' to the wire 23. The winding of the relay T^{12} is connected to the wire 24 in multiple with the actuating winding of the relay T^3 , while the relays T^{13} , 85 T^4 and T^5 are connected in multiple respectively with the actuating winding of the relay T^3 , T^4 and T^5 . The other terminal of each of the units relays is connected to a common wire 14 leading to the normally open contact f^2 of the relay F . In the foregoing description it will be seen if battery is placed on the wire 23 by the relay W' , the relay T' will be operated, being connected to ground through contacts of 90 the relay F , but the relay T^{11} will not be affected as the common wire 14 is disconnected from ground. The relay F is in reality the switching relay and is operated after the first set of impulses, by the operator depressing the button X' which connects ground to the relay E' , which in turn closes the circuit of the relay F which remains locked through the contacts f and f' and under control of the relay D' . The operation 95 of the relay F removes ground from the common wire 15 of the tens set of relays and connects ground to the common wire 14 of the units set of relays. This relay also by closing the contacts f^5 and f^6 places battery on the locking wire 16 which thereupon keeps the relay which was last operated in an energized condition. When the button X' is depressed, operating the relay E' , the contacts e^5 and e^6 are broken, releasing the 100 relay F' , (which has been locked up through the contacts f^7 — f^8) thereupon removing battery from the common wire 13 leading to the locking contacts of the relays in the set W . The relays of the set W are now re- 105 110 115 120 125 130

stored to their normal position and are ready to be operated a second time by the button X. Instead of operating or controlling the tens relays, they now control the units relays as the circuit has been switched in the relay F. The operation of the relays W the second time is the same as that already described, the only difference being that after the second set of impulses has been sent, the relays are not released as the operator does not depress the button X'. These relays remaining energized after the second set of impulses enable me to use a single winding on the units relays as battery remains on the particular individual wire leading to the selected units relay. After the operator has sent the second set of impulses, she depresses the buttons X² and X³ placing generator current on the calling 20 end of the trunk and opens the answering end of the trunk to prevent the calling subscriber receiving generator current back over his line. At the end of the conversation when the operator withdraws the plug 25 P, all the relays become deenergized and the apparatus is restored to its normal position.

The operation of my system is as follows: The subscriber at station A removing his receiver closes the circuit of the line relay M which in turn closes the circuit of the line lamp L, notifying the operator of a call. The operator receiving the signal, inserts the plug P into the jack J, energizing the relays M' and D', the relay D' being connected to battery while the relay M' is connected to ground. The energizing of the relay M' disconnects the line relay M and connects the line wires 1 and 2 through the extensions 3 and 4 to the springs j and j' 40 of the jack J. Upon asking the number and receiving the same she immediately depresses the button X a number of times corresponding to the number asked for. Suppose the number asked for was 32. She will, therefore, depress the button X four times. When the button is first depressed, the relay E is energized and closes the circuit of the relay F' by the following path: battery B, 21, 20, e³, e⁴, 22, F' to ground. The operation of this relay places battery on the contacts e' by the following path: battery B, 21, 20, e⁸, e⁹, 28, f¹⁰, f⁹, 13, to e'. The relay F' also places battery on the extension wire 13 which is common to all the locking 55 contacts of the relays in the set W. Battery is now placed on the wire 18 through the contacts e and e', but the contacts h and h' of the relay H' are open at this juncture and the relay W' is not affected. After the first 60 impulse the relay E becoming deenergized, closes the contacts e' and e² placing battery on the wire 19 through the contacts w' and w to the relay H' and ground. The relay H' thereupon becomes energized and locks 65 itself through the contacts h² and h³ leading

to the locking wire 13. The contacts h and h' are also closed thus connecting the wire 18 to the relay W' through the contacts h⁴ and h⁵ of the relay H². The operator now depresses the button X the second time, energizing the relay E which in turn closes the circuit of the relay W' by the path already traced. After the second impulse the contacts e' and e² being closed the circuit of the relay H² is completed through the 70 contacts w' and w² of the relay W'. The operator depressing the button the first time does not operate any of the selective relays W', W², etc., but simply closes the circuit of the relay H' placing the set W', W², etc., 80 in condition to be operated. So of course it follows that the first impulse is only a preliminary start as it does not operate any of the relays in Fig. 3, and instead of depressing the button three times she has to depress it four times to operate the third relay. The operator depressing the button the third time first closes the circuit of the relay W² through the contact h⁴ and h²⁰ of the relay H² and second the relay H³ through the contact w⁸ and w⁹ of the relay W². The fourth time the button is depressed the relay W³ and H⁴ are operated. When the relay W' was operated at the second impulse the circuit of the first tens relay T' was closed by 95 the following path: battery B, 21, w³⁷, w³⁶, w²⁹, w³⁰, w²¹, w²², w¹³, w¹⁴, w⁶, w⁵, 23, T', 15, f⁴, f³, to ground. This relay T' does not remain locked as the common locking wire 16 is open in the relay F. At the third impulse the operation of the relay W² closes the circuit of the relay T² over the wire 24 and at the same time opens the circuit of the relay T' by breaking the contacts w¹⁴ and w¹³. At the fourth impulse the relay W³ 100 operating, closes the circuit of the relay T³ and at the same time opens the circuit of the relay T² by breaking the contacts w²² and w²¹. As the relay T³ contains the contacts leading to the desired line the operator depresses the button X' and then proceeds to select No. 2 units relay. The operating of the button X' closes the circuit of the relay E' which in turn closes the circuit of the switching relay F. In the relay E' the 110 opening of the contacts e⁸ and e⁹ and e⁵ and e⁶, disconnects the relay F' and releases all of the relays in the set W. The operating of the relay F connects battery to the wire 16 which maintains the circuit of the relay T³ which is energized at this time. The relay T³ is the only one of the set that can be affected by battery being placed on wire 16 as its locking circuit is connected to ground through its contacts t²⁵ and t²⁰. 115 Ground is now removed from the common wire 15 of the tens relays by the opening of the contacts f³ and f⁴, and ground is connected to the common wire 14 of the units relays. The relay set W is now again in 120 125 130

position to be operated by the second set of impulses, the only difference being that the units relays are now controlled in place of the tens relays. The operator sends in three 5 impulses to select the second units relay T^{12} . Relays in the set W are operated in the same manner as before and when the relay W^2 is selected, the circuit of the relay T^{12} is closed through the wire 24. The calling 10 subscriber is now connected to the called subscriber through the cord circuit and contacts of the tens and units relays, and the operator depressing the buttons X^2 and X^3 , places generator current on the called line. 15 By means of the supervisory lamp L^2 she is enabled to tell when the called party answers his telephone. At the end of the conversation when both parties hang up, the supervisory lamps L' and L^2 glow, notifying the 20 operator of the fact who at once withdraws the plug P from the jack J . The withdrawing of the plug removes battery from the wires 9 and 11, deenergizing the relays F and F' thereby releasing relays in the set W 25 and the tens and units relays in Fig. 3, thus restoring all apparatus to its normal or idle position.

Having thus described my invention, what I claim and desire to secure by Letters Patent is:

1. In a telephone exchange system, a plurality of lines and means to selectively connect therewith comprising a series of relays arranged in numerical order corresponding 35 to the digits to be selected and adapted to be energized successively by current impulses, the energization of each succeeding relay being dependent upon the energization of those preceding it.
2. In a telephone exchange system, means for selecting wanted lines comprising a series of relays brought into association with a calling line for that purpose, local controlling circuits for said relays less in number than the number of relays, and means for sending current impulses over said controlling circuits to energize the selective relays in step by step succession.
3. In a telephone exchange system, a plurality of talking circuits, and means for selectively interconnecting the same composed of contact devices and controlling means thereof comprising a series of relays adapted to be operated step by step in succession, the circuit of each succeeding relay being partly controlled by those preceding it, whereby the number wanted is reached by building up the controlling circuit.
4. In a telephone exchange system, connecting means and selective controlling means therefor consisting of a double set of interlocking relays, a double controlling circuit, and means to apply current impulses to the two sides of the circuit alternately, 60 whereby the relays may be operated step by

step in sequence and may thereby be caused to select any desired circuit.

5. In a telephone exchange system, a plurality of line circuits to be interconnected, means associated with said lines for indicating a call, manually operated connective means for answering a call and extending the line calling to the switching apparatus, a group or groups of relays constituting said switching apparatus, and means for controlling the same, itself controlled over a portion of the talking circuit. 70

6. In a telephone exchange system, a plurality of line circuits, means associated with each line for indicating a call, means for extending the line in response to the call to automatic switching apparatus, connecting relays constituting said switching apparatus, and controlling relays for the connecting relays. 80

7. In a telephone exchange system, line connecting means comprising a double digit system of relays determining the connection of a calling trunk with a desired line, and a series of interlocking relays responding to 90 step by step impulses and controlling the double digit relays. 85

8. In a telephone exchange system, a plurality of line circuits each having a telephone set and signal device at the substation, and an answering jack with an associated calling signal at the central office, answering plugs adapted to coöperate with said answering jacks, an automatic connector switching apparatus connected by a 100 trunk circuit to each plug, selective actuating means for said switching apparatus directly connected thereto when set, and manual means separately operated to preset the actuating means. 95

9. In a telephone exchange system, a plurality of line circuits, a plurality of connecting trunks less in number than the number of line circuits, with means to connect an idle trunk to a calling line, automatic 110 switching apparatus forming the terminal of each trunk, selective actuating means for the switching apparatus also associated with the trunk and exclusively controlling the actuation of the switching apparatus, 115 which actuating means is operated in advance of the operation of the switching apparatus, and separate and additional manually operative means for so operating said actuating means. 120

10. In a telephone exchange system, a plurality of line circuits, a number of connecting trunks less than the number of lines, means for connecting an idle trunk to a calling line, an automatic switching apparatus forming the calling terminal of each trunk and adapted when actuated to select any desired line circuit and connect the trunk therewith, actuating means for said switching apparatus composed of elements 125 130

- adapted to be selectively operated in step by step progression, and means manually controlled by an operator for presetting said actuating means.
- 5 11. In a telephone exchange system, a plurality of line circuits, a plurality of connecting trunks less in number than the line circuits, a group of connecting relays associated with each trunk and adapted to connect the same selectively to any one of the other circuits, a step by step controlling switching device adapted to select and connect said relays in proper order to complete any desired connection, and manually operated means for actuating said step by step device.
- 10 12. In a telephone exchange system, a plurality of line circuits and a plurality of trunks less in number than the number 20 of line circuits, with means to connect an idle trunk with a calling line, automatic switching apparatus connected to and constituting the calling terminal for each trunk, a set of controlling relays adapted when set to selectively actuate said switching apparatus, and manually operated means for antecedently setting said relays for the selection of any desired number by the switching apparatus.
- 15 13. In a telephone system, two associated sets of selective relays, controlling wires common thereto, an actuating wire individual to each set, divided into sections controlled by contacts of relays in the other set, and means to build up said actuating wires to energize any desired relay of either set by sending impulses through the two actuating wires in succession.
- 20 14. In a telephone system, a double set 40 of selecting relays containing banks of line contacts, a set of controlling relays whose armatures control the energization of the selecting relays, and manual means for operating said controlling relays so as to operate the proper combination of selecting relays for closing any desired line circuits.
- 25 15. In a telephone exchange system, a line circuit, a central office automatic connective switching apparatus associated therewith, actuating means for said switching apparatus adapted to set the same to any desired digit by a single direct application of current, and pre-setting means for the actuating means adapted to selectively operate the same in successive steps.
- 30 16. A selecting device for a telephone or signaling system comprising two sets of relays, one set controlling operating wires, the second set controlling the connection of the individual relays of the first set to an actuating wire, and means whereby the relays of the first set may severally and respectively control the circuits of the corresponding relays of the second set, so that selective connection with the controlling wires can only be attained by associated actuation of predetermined relays in the two sets.
- 35 17. In a telephone exchange system, a plurality of line circuits to be interconnected, a plurality of maunal connective 70 terminals less in number than the number of line circuits, and a plurality of relays for each connective terminal, in decimal relation with each other, adapted when actuated to automatically connect a line circuit with a connective terminal.
- 40 18. In a telephone exchange system, subscribers' lines, connective links therefor provided with automatic connective apparatus comprising digital sets of connecting relays and impulse actuated governing means therefor, an impulse sending device, a signaling device and a common battery at the central station arranged to supply talking current for the subscribers' lines, and energizing current for the impulse sending device and the automatic connective apparatus.
- 45 In testimony whereof I affix my signature in presence of two witnesses.
- EDWARD E. CLEMENT.
